UNITED STATES PATENT OFFICE.

MAXEMILIAN E. KOEHLER, OF WASHINGTON, DISTRICT OF COLUMBIA.

ATTACHMENT FOR IRONING BOARDS.

Application filed June 4, 1921. Serial No. 474,925.

To all whom it may concern:

Be it known that I, MAXEMILIAN E. KOEHLER, a citizen of the United States, residing at 1315 Shepherd Street, Washington, District of Columbia, have invented certain new and useful Improvements in Attachments for Ironing Boards, of which the following is a specification.

This invention relates to improvements in attachments for ironing boards.

When using an ironing board the operator usually lifts the iron at the end of an ironing operation and places it on a stand to avoid burning or staining the cloth. Then again in placing a skirt or other article of apparel on the board the latter is tilted at one end and almost invariably the iron falls to the floor.

According to my invention I aim to overcome these difficulties in that I provide means for accommodating the iron at the end of the board, so that the actual operation of lifting the iron is dispensed with, and in addition provide means for retaining the iron on the board when the latter is elevated to place a skirt or other garment thereon.

A further object of the invention is the provision of means for clamping the attachment on an ironing board to insure its maintaining its position with relation to the board and the cover thereof.

A still further object of the invention is the provision of means for conveniently protecting the edge of the ironing board cloth on the edge of the attachment to present a smooth and uninterrupted surface for the iron.

The invention also comprehends improvements in the details of construction and arrangement of parts which will be herein-after described and particularly pointed out in the claims.

In the drawings:—

Figure 1 is a perspective view of the attachment applied to an ironing board.

Figure 2 is a central vertical section.

Figure 3 is a bottom plan view.

Figure 4 is a section on line 4—4 of Figure 3.

1 indicates the attachment which in plan view is somewhat fan-shaped, to present a broad entrance surface for an iron. The attachment comprises a body portion 2, which inclines downwardly at the front end 3, the incline portion merging into a sub-

stantially horizontal portion 4. From the side edges of the incline portion, and extending downwardly therefrom, are flanges 5, and from the side and rear edges of the horizontal portion 4 extend downwardly turned flanges 6, the flanges resting on the ironing board to afford supports for the attachment. Between the supports 5 and 6 on opposite sides of the attachment are perforated ears 7, and from the rear edge extends an ear 8.

In addition to the supports 5 and 6, other supports 9, are stamped from the metal and extend downwardly and engage the board to steady the attachment when in use. On the inclined portion 3, are several, more or less beads 10, to form tracks for an iron to ride on when the operator pushes or pulls the iron up on the attachment. At the wide or front end of the attachment there is formed a lip or shelf 11, which fits flat on the board, and in rear of the shelf is formed an offset 12, against and into which fits the edge of the ironing board covering, the flange being of such depth as to substantially correspond to the thickness of the covering, but if the latter is not of such thickness, then a filler may be employed. In either event it is preferable that the top surface of the cloth be on a plane with the incline surface 4, to present a continuous surface for the iron to ride on.

It is highly important that the attachment be held rigid on the board and to accomplish this the attachment is sufficiently resilient to yield at or about the juncture of the inclined and horizontal portions, and in addition a special clamp is provided. When the attachment is free from the gripping action of the clamp, and due to the resiliency of the metal the front and rear portions of the body portion bend slightly toward each other, as shown in dotted lines in Figure 2, with the result that normally the side flanges 5 and 6 will not bear squarely on the ironing board. The clamp 15, comprises a pair of hooked arms having an inner rounded or loop end, and an intermediate spring 17, the latter being held in operative position by a loop 18, struck from the metal. Each hook member consists of a wire loop 16, the legs of which are extended beyond the sides of the body portion and are bent to form hooks 19, to engage the side edge and bottom of the ironing board. The loop ends of the clamps pass through eyes formed at the opposite

ends of the spring as clearly shown in the drawing. To prevent the attachment pulling away from the board when the latter is tilted, slots 20, are formed in the side flanges 6, and through these slots the legs of the loops pass. A guard 21, in the form of a stiff wire, is bent at its ends to pass through the perforations in the ears 7, and at the rear, said wire is bent downwardly and twisted on itself and engages a loop or eye formed in the ear 8. The guard is spaced from the body portion at the rear in order to catch an iron if the latter should tend to fall from the attachment when the same is in use.

In operation, the attachment is placed on top of an ironing board near one end thereof, the front edge or lip 12, being slipped under the end of the covering, until the edge of the latter abuts against the flange 12, then the clamping members are pulled out laterally until the hooks are beyond the edges of the board, and they are then pressed down below the level of the bottom of said board and released. The tension of the spring draws the hooks up to snugly engage the edges of the board and a firm locking engagement of the parts takes place. The lateral pull of the hook members, and the shape of the hook end tends to pull the body portion down on the board, with the result that the metal yields slightly and the bottom edges of the side flanges 5 and 6 are brought squarely down and in contact with the surface of the ironing board, which effects a rigid engagement of the attachment with said board.

At the end of an ironing operation, the operator simply forces the iron up the inclined portion and over the beads or tracks 10, to the horizontal portion, the effort in performing this movement being substantially nothing more than that required when

ironing. Obviously when the ironing board is tilted and the iron slides toward the rear it is caught by the guard and retained on the attachment.

What I claim is:—

1. An attachment for holding an iron on an ironing board, comprising a metal body portion inclined at its forward end and merging into a substantially horizontal portion, a clamp comprising a spring and two oppositely disposed hook members attached to the spring and extending through openings formed in the body portion, whereby to form a clamp to secure the attachment to an ironing board. 50

2. An attachment for holding an iron on an ironing board, comprising a metal body portion inclined at its forward end and merging into a substantially horizontal portion, a loop formed on the body portion, a spring extending through the loop and engaging under the bottom of the body portion, and a pair of hook members engaging the ends of the spring and extending through openings formed in the body portion whereby to form a clamp to hold the attachment to an ironing board. 60

3. An attachment for holding an iron on an ironing board, comprising a body portion in part horizontal and in part inclined, the horizontal portion having integral depending sections to bear on the ironing board and the inclined portion having depending sections to bear on the ironing board, and clamping means for the attachment operating through the depending sections of the horizontal portion and adapted 70 to removably engage the edges of the ironing board. 75

In testimony whereof I affix my signature.

MAXEMILIAN E. KOEHLER.
